PUMPING APPARATUS

Filed Jan. 15, 1936

5 Sheets-Sheet 4

Fig. 9.

The drawing shows a cross-section of a mechanical component, possibly a bearing housing. It features a central vertical shaft with a shoulder. A housing is attached to the top, with a shoulder and a bore. The housing has a flange on the left side. Various dimensions are indicated: 58, 96, 94, 99, 84, 91, 92, 79, 89, 88, 77, 75, and 89. The bottom part of the drawing is filled with a cross-hatched pattern.

This technical drawing illustrates a cross-sectional view of a device assembly. The assembly includes a base structure with a central vertical tube. A horizontal plate, labeled 87, is positioned above the tube. A vertical rib, labeled 88, is located on the left side of the tube. The tube itself is marked with several numbers: 73 on the left, 77, 81, 70, 76, and 78 on the right. Above the tube, a rectangular component is labeled 62, 58, 80, 65, 69, 66, and 30. A small arrow points to the right at the bottom right corner of the drawing.

PUMPING APPARATUS

Warren H. De Lancey, West Springfield, Mass., assignor to Gilbert & Barker Manufacturing Company, West Springfield, Mass., a corporation of Massachusetts

Application January 15, 1936, Serial No. 59,254

7 Claims. (CL 103—113)

This invention relates to improvements in apparatus for pumping relatively volatile liquids, such for example as gasoline. The pumping apparatus has been particularly designed to meet the special conditions which are encountered in dispensing accurately measured units of gasoline and, while capable of other adaptations, is especially suitable for the particular use described.

The invention seeks to utilize in dispensing apparatus of this class, the well-recognized advantages which the centrifugal type pump has over the displacement type pump which at present is the type most widely used in such dispensing apparatus. The centrifugal pump is smoother and more quiet in operation; will deliver the required quantity of liquid in a minimum of time; consumes less power; enables substantial savings in manufacturing costs; and is less likely to require servicing. In addition, this type of pump can readily be utilized to secure through the centrifugal action of the pump itself, a very efficient separation of air from the pumped liquid and a small displacement pump, necessary for priming the centrifugal pump, can be made to perform the additional function of scavenging the separated air.

This invention has for one object to provide in a pumping apparatus for gasoline or the like, having a centrifugal pump designed to pump the liquid and also cause, through its centrifugal action, a separation of air from the liquid and a displacement pump for priming the centrifugal pump and scavenging the separated air, an effective means to insure that the air-free liquid discharged from the centrifugal pump maintains its air-free appearance when delivered to the customer.

With the forms of centrifugal pumps heretofore proposed for use in gasoline dispensers, it can and does happen at certain times and under certain conditions, that the gasoline will become partially vaporized in the discharge chamber or passages of the centrifugal pump and, when this occurs, the liquid discharged has a foamy appearance due to the presence of innumerable small bubbles of gasoline vapor. The air-free liquid does not actually appear so and the customer naturally objects. It is not enough to free the gasoline from air but it must also be delivered to the customer in clear condition with an air-free appearance and this is effected by my invention.

The invention also has for an object to provide, in an apparatus of the class described, an improved structural combination for pumping

gasoline or the like and for effecting the separation of air from the liquid and the scavenging of the separated air.

The invention has many other objects, relating to improvements in the structure and in the arrangement of parts in a motor-driven pumping unit of the class described, and these will best appear as the detailed description proceeds.

The invention will be disclosed with reference to the accompanying drawings, in which:

Fig. 1 is a small scale elevational view of a gasoline dispensing apparatus embodying the invention, certain parts of the casing of the apparatus being broken away to reveal interior mechanism;

Fig. 2 is a fragmentary elevational view taken at right angles to Fig. 1;

Fig. 3 is a sectional elevational view showing in full detail the liquid recovery device used in connection with the air separating means of the apparatus;

Fig. 4 is an elevational view of the motor-driven pumping unit, drawn to a larger scale,—the lower and pump portion of the unit being shown in section;

Figs. 5, 6, 7, 8 and 9 are sectional plan views taken respectively on the lines 5—5, 6—6, 1—1, 8—8 and 9—9 of Fig. 4;

Fig. 10 is a fragmentary cross sectional view taken on the line 10—10 of Fig. 9;

Fig. 11 is a sectional plan view showing a modification in the shape of the inlet port of the displacement pump;

Fig. 12 is a fragmentary sectional view, taken similarly to Fig. 4 and showing a detail of the centrifugal pump;

Fig. 13 is a fragmentary sectional elevational view, taken similarly to Fig. 4, and showing a modification in the centrifugal pump construction; and

Fig. 14 is a sectional plan view taken on the line 14—14 of Fig. 13.

Referring to these drawings; the invention is shown in Fig. 1 embodied in a gasoline dispensing apparatus of the so-called meter type. The apparatus, therein illustrated in more or less conventional form, is intended to show the usual environment in which the invention is used, and will serve as an illustrative example of one of many types of such apparatus with which the invention may be used.

As shown in Fig. 1, the apparatus is for the most part contained within a casing 15, having upstanding column-like corner portions 16 from

- which most of the parts are supported. This casing is closed at the top by a cap 17 which usually carries an ornamental globe 18. The pumping unit, shown separately in Fig. 4, is mounted near the lower part of the casing, resting on a plate 19 which is secured to the portions 16. The unit is fixed to said plate by bolts 20. This unit includes an electric motor 21, on the upper end plate 22 of which is formed a box 23. 10 This box houses the usual control switch which has an operating lever 24. The switch may be operated by a lever 25, located outside casing 15 and fixed to a shaft 26 which extends inside the casing and carries an arm 27, connected by a link 15 28 to lever 24. The part 22' is a fitting for connection to a conduit through which the electric wires are led to the motor. This part 22' is connected to the casing 22 by a screw 28' on which the part 22' may swivel. 20 The motor-driven pumping unit draws gasoline up from an underground supply tank (not shown) through a suction pipe shown in part at 28, and in the suction pipe is the usual check valve which prevents downward or return flow. 25 Gasoline is discharged from the pumping unit through a pipe 30 which is connected to the inlet of a meter 31. The meter may be of any suitable type and has associated therewith any suitable form of registering means, herein conventionally indicated at 32, which are driven from the meter by a shaft 33. The gasoline leaves the meter by way of a pipe 34 which extends through the casing 15 for connection to a flexible hose 35, having at its delivery end a hose 36, equipped with a normally closed valve which can be manually opened by a lever 37. This nozzle is of the same general type as is shown in U. S. Patent No. 1,870,918, granted August 9, 1932, on an invention of Joseph A. 40 Logan and may, and preferably does, have the outwardly opening check valve shown in said patent. Usually and as shown herein, there is interposed between pipe 34 and hose 35, a visible discharge indicator 38 of any suitable form. 45 When the apparatus is not in use, the nozzle 36 is hung up on a support 39 (see also Fig. 2) fixed to and projecting outwardly from casing 15 and when thus hung up, movement of the switch lever 25 in the direction necessary to start motor 21 is prevented by abutment with the nozzle, as will be clear from Fig. 2. When the nozzle is removed from its support, lever 25 may be swung in a clockwise direction into vertical position to start the motor. 50 The pumping unit has provisions for separating from the gasoline any air that may be passed up pipe 29 and such air, and usually some gasoline with it, is expelled through a pipe 40 which leads upwardly to a tank-like device 41. This device, as shown in Fig. 3, affords within it a chamber 44 into the upper part of which the air and gasoline is delivered. In this chamber the gasoline and air are gravitationally separated and the air passes out to the atmosphere. In detail, the air leaves through ports 45 formed in the upper wall of chamber 44, passing into an overlying float chamber 46, from which the air escapes through an outlet 47 in the top wall of such chamber. A cap 49 covers outlet 47 and 60 contains a screen 48 through which the air must pass to reach the outlet 49' of cap 49. The outlet 47 can be closed by a valve 50 fixed to a float 51 in chamber 46, if and when necessary because of some unusual and abnormal condition, to prevent gasoline from passing out

through the outlet. The gasoline accumulating in chamber 44, eventually raises a float 52 which is mounted to slide on a guide rod 53 fixed to the lower wall of chamber 44. The rising float 52' operates through a lever 54, pivoted at 55 to 5 raise a valve 56 and allow gasoline to enter a pipe 57 which, as shown in Fig. 1, extends downwardly and is connected to suction pipe 29. Valve 56 opens from time to time as necessary to prevent undue accumulation of gasoline in 10 chamber 44 and closes before all the gasoline in the chamber is exhausted so that air cannot pass back through pipe 57 to the suction pipe 29.

The apparatus, thus far described, will serve as one illustrative example of the general class with 15 which the invention may be used. The invention is more particularly concerned with the pumping unit, wherefore it follows that the details of the apparatus described are not essential and that the invention is not limited thereto.

The pumping unit is best shown in Fig. 4. This unit, as already described, is driven by an electric motor 21, having the end plate 22 and another and specially-formed end plate 58—such plates being suitably held together as by a series 25 of tie rods 59. These rods are threaded into lugs on the upper end plate and slidably fit and pass through corresponding lugs 60 on the lower end plate. Nuts 61, threaded on the lower ends of rods 59, serve to clamp the head 58 in place and 30 also enable its convenient removal from the rest of the motor whenever necessary or desired.

This end plate 58 is hollow cylindrical in form, closed at its lower end by a wall 62, from which upstands in concentrical relation a hub-like portion 63 of stepped cylindrical formation. This portion 63 is connected to the cylindrical wall by a series of radial ribs 64 (Fig. 9) arranged in angularly spaced relation. The plate 58 at its lower end has an annular flange 65, resting upon a corresponding flange 66 formed on a lower casing member 67. It also has a cylindrical flange 68 fitted into a corresponding recess in the lower casing 67. A gasket 69 is interposed between flanges 65 and 66 and a gasket 70 is 45 interposed between the end face of flange 68 and the lower wall of the recess into which it fits. The two flanges 65 and 66 are clamped together, with the gaskets between them to seal the joints, by a series of angularly spaced bolts 71 (Fig. 9). The flange 66 has a series (four as shown in Fig. 5) of lugs 72 projecting outwardly beyond the overlying flange 65 to receive the bolts 20, here- 50 tofore described as securing the pumping unit to its supporting means 19. It will thus be seen 55 that the lower casing 67 only is bolted to such supporting means 19. The bolts 71 may be removed to enable removal of the motor including the lower head 58 and other parts later to be described, without removing the bolts 20, thereby 60 leaving the lower casing tightly bolted in place. The pipes 29, 30 and 40, being all the pipe connections to the pumping unit, connect with the lower casing. Thus, the pumping unit, including the motor and all parts driven therefrom and all 65 parts housed in end plate 58, may be removed without breaking any pipe connections.

The lower casing 67 is formed to provide a central boss 73, into which the suction pipe 29 is threaded and in which is a cylindrical passage 74, 70 the upper end of which converges into an opening 75 of smaller diameter, forming the inlet eye of the centrifugal pump. Casing 67 is also formed to provide a discharge chamber 76 of annular form, encompassing the boss 73 and connected 75

thereto by a circular top wall 71 which extends part way across the upper end of chamber 76 in overhanging relation and through which the opening 75 extends. The casing 67 is also formed with an outlet 78 (Fig. 10) for chamber 76 and into this outlet pipe 30 is threaded. The lower wall 62 of end plate 58 and the top wall 71 of the lower casing together form the housing of a centrifugal pump and are suitably recessed as shown, to form a pump chamber 79. This chamber diminishes in height from a maximum near the central opening 75 to a minimum at its outer peripheral part where it converges to a very narrow outlet slot 80. This slot, which forms a diffuser, extends entirely around the chamber and communicates with the underlying outlet chamber 76 by a downwardly curving slot 81 which diverges in the direction of liquid flow. In the chamber 79 is located the impeller 82 of a centrifugal pump. The construction 20 of this impeller is such that it may be, and preferably is formed by die casting. As shown, the impeller is of the open type. It has a central hub 83 keyed to the lower end of the armature shaft 84 of motor 21 and clamped against a shoulder 85 on 25 said shaft by a nut 86. Integral with the hub 83 is a disc 87 having a flat upper face and a lower face of frusto-conical form. Depending from this lower face are a series of angularly-spaced impeller vanes 88 the inner ends of which are spaced 30 from hub 83. Formed in disc 87 between the inner ends of vanes 88 and hub 83 are a series of vertical holes 89. These holes enable fluids, including all the air and gases in or with the volatile liquid and normally also some of the liquid itself, 35 to pass vertically upward to an overlying displacement pump. These holes 89 open into a central area above the impeller, which area is partitioned off from the remaining area by an upstanding annular flange or collar 89' formed on the impeller.

The displacement pump is desirably located immediately above the centrifugal pump in a cylindrical chamber 90 formed in the lower portion of hub 63 and opening into the aforesaid central area 45 of the chamber 79 of the centrifugal pump. While various forms of displacement pumps may be used for the purpose, it is preferred to use the particular form of pump shown in Fig. 7. Such pump comprises a pinion gear 91, keyed to the shaft 84 of motor 21, and an annular gear 92, rotating about an axis 93, eccentric to shaft 84. The 50 annular gear turns in a cylindrical recess formed in a center plate 94 concentric with axis 93. Plate 94 is clamped between two end plates 95 and 96 through which shaft 84 passes with ample clearance, as indicated. The provision of this clearance is for the purpose of avoiding the wear on the shaft 84 which would otherwise occur if it 55 made contact with these plates which, because of the nature of the pump, have to be hardened and lapped to engage with an exceedingly close fit the end faces of the gears 91 and 92. A series of cap screws 97 pass through the plates 94, 95 and 96 and thread into hub 63 to fasten the displacement pump in place. In addition, other screws 97' pass through plates 96 and 94 and thread into plate 95 to clamp the plates together and maintain the parts of the displacement pump in assembled relation when the screws 97 are removed.

70 The plate 95 is formed with an outlet port 98 of the form shown in Figs. 4 and 6 and the plate 96 is formed with an inlet port 99 of the form shown in Figs. 4 and 8. The plate 96 is recessed to rotatably receive the flange 89' (see Fig. 12 where this 75 arrangement has been separately shown to avoid

confusion in Fig. 4). The inlet port 99 lies inside this groove and flange and directly communicates with said central area. Particularly, the port 99 directly overlies the impeller 82 of the centrifugal pump at a radial location which is close enough to 5 the axis thereof to receive all the air and gases collected in the suction pipe as will appear. The outlet port 98 communicates with an overlying recess 100, formed in hub 63 and from which a passage 101 extends radially outward through one of the webs 64 (Figs. 4 and 9) to the periphery of end plate 58—the outer end of this passage being closed by a plug 102. Communicating at one end with passage 101 is a passage 103 which extends downwardly to and through flange 66 and registers with a passage 104 which extends from the upper surface of flange 66 downwardly to a lateral outlet passage 105, formed in the base member 67 and connected to the described pipe 40.

The inner rotor 91 of the displacement pump 20 is driven in the direction of the arrow shown in Fig. 7 by the motor on the shaft 84 of which it is mounted. The rotor 91 in turn rotates the outer and annular rotor about the axis 93. The inner rotor has one less tooth than the outer rotor and 25 the contours of the teeth and the spaces between them are designed so that the teeth of each continuously slide in close contact over the contour of the other. In the priming pump the teeth of one rotor are generated by the teeth of the other rotor. 30 The two rotors present a series of closed pockets 106 which gradually expand in volume as the rotors turn from the full mesh position 107 to the open mesh position 107' and then gradually contract in volume, as the rotors turn from the last 35 named position back to the position 107. I prefer to make this displacement pump according to the principles of rotor construction used in either of the Hill Patents No. 1,682,564 and No. 1,682,565 of Aug. 28, 1928. During part of the time while 40 these pockets are expanding in volume they communicate with the inlet port 99 and thus, due to the suction created by the increase in volume of these pockets, fluid is drawn up through the port 99 to fill the pockets. Then each pocket becomes 45 successively cut off from port 99 and shortly after moves into position where it can communicate with outlet port 98. Then as the pockets 106 gradually decrease in volume, the fluid is expressed through the port 98 into the outlet pas- 50 sages above described.

A modification in the shape of the inlet port is shown in Fig. 11 at 99'. The boundary walls of this port, instead of being vertical are inclined to the vertical and approximate a helix. The fluid 55 whirling in the pump chamber in the direction of the arrow shown in Fig. 11, enters the port in a more natural and smoother manner. The kinetic energy of the fluid is to some degree utilized to cause it to enter the inlet port 99' rather than re- 60 lying solely on the partial vacuum created by the displacement pump.

Above the displacement pump, the hub 63 is bored out to receive an anti-friction bearing. Because of the exceedingly close clearances between 65 the rotors of the displacement pump, it is essential that the motor shaft 84 be held in very close alignment. An ordinary sleeve bearing such as is ordinarily supplied in electric motors would not suffice because the usual clearance of one to 70 two thousandths of an inch would allow too great an eccentricity of movement of the shaft for the closely interfitting rotors. By preference, of the various forms of bearings available, a ball bearing having the inner and outer races 108 and 109 75

with intervening balls 110, is employed to secure a mounting of the shaft which will hold it with the close degree of accuracy required in the intended alignment. For similar reasons, the displacement pump is located as closely as possible to the bearing and the impeller of the centrifugal pump is located as closely as possible to the displacement pump. The overhang of the shaft below the bearing is made as short as is feasible to 10 avoid the possibility of any eccentric movement of the shaft due to whipping or centrifugal action.

Actually, the bearing and the displacement pump are spaced because of the necessity of providing a sealing means to prevent escape of gasoline from the displacement pump around the shaft 84. Such means is mounted in a cylindrical chamber 111, formed within a tube 112 which extends between plate 85 and the race 108. The sealing means comprises a cup-shaped metallic member 113 having an opening in its end face through which shaft 84 passes, and within the cup portion a packing washer 114 tightly fitting the shaft. A spring 115 acting between the race 108 and the washer 114, presses the latter against 20 the bottom of the cup and presses the outer end face of the cup against the lapped upper face of pump plate 85. The cup 113 is caused to turn with shaft 84 because of the frictional engagement of the washer with both cup and shaft. The 25 spring 115 turns with shaft 84 since it presses at one end against the race 108 which is fixed on the shaft, and at the other end against washer 114 which also is fixed to the shaft.

The chamber which houses the sealing means is 30 vented by a radial passage 116 formed in one of the radial webs 64 and extending from tube 112 outward to the periphery of end plate 58 for communication with the atmosphere. An annular groove 117 is formed in the outer periphery of 35 tube 112 and communicates with passage 116 and a plurality of radial holes 118 are provided in the tube to enable communication between its interior and groove 117. This venting means provides an easy path for the escape of inflammable vapors should any such leak from the displacement pump. Except for this means, the vapor might, in the event of leakage, creep along the shaft, entering the casing of motor 21 and the housing 23 of the motor switch, and be exploded by an electric arc from the switch.

Above the ball bearing described, there is a portion 119 formed on the upper part of hub 63 and such portion appears like an ordinary sleeve bearing, encompassing the shaft with a fit comparable to that used in a sleeve bearing. This portion 119 is provided as a safeguard in the event that an explosion should occur inside the motor casing. The purpose of portion 119 is to prevent flame from penetrating into the displacement pump and causing an explosion there. The portion 119 thus serves as a flame arrester and not in any sense as a bearing for shaft 84.

The motor 21 may have both bearings for shaft 84 constructed as described. It is not, however, essential that the upper bearing be so constructed. That is, a small radial play between the shaft and upper bearing of an amount within the usual tolerances of a sleeve bearing will cause no difficulty. The small play in the upper bearing results in a greatly reduced play of the shaft at the point where the rotor 81 is attached to it because the length of the shaft between the bearings is several times the length of the shaft between the lower bearing and rotor 81.

It is not essential that the diffuser for the cen-

trifugal pump be of the particular form shown, viz., the two closely spaced annular walls with the narrow slot 88 therebetween. Instead of that type of diffuser, I may use any other suitable type such, for example, as that shown in Figs. 13 and 14. The diffuser in this case comprises a circular series of angularly spaced vanes 120, surrounding the impeller and mounted between the upper and lower vertically-spaced parallel walls 121 and 122, being fixed to or integral with one of such walls. These walls, it will be noted, are more widely spaced than the corresponding walls in Fig. 4. This enables a substantial reduction in the friction loss to be effected. These vanes 120 afford between them specially shaped 15 passages 123 which gradually enlarge in the direction of the flow of liquid through them and which function to gradually reduce the velocity of the liquid leaving the impeller and to efficiently transform the kinetic energy of the liquid into 20 pressure energy. This form of diffuser, like the former, avoids the dissipation in eddies of the kinetic energy of the liquid and avoids cavitation, but it accomplishes these results with less of a friction loss.

This form of diffuser is, however, not widely used for relatively small centrifugal pumps because it is difficult and expensive to accurately form and finish the vanes, which due to space limitations have to be very small. These disadvantages, I overcome by forming the vanes by die casting. The vanes are integral parts of a removable plate secured to one or the other of the castings 58 or 67. While these castings 58 or 67 do not lend themselves to manufacture by die casting, a small section such as shown in Figs. 13 and 14 may readily be die cast. In this case, I have provided two die cast plates 124 and 125 which line the inner and confronting faces of the castings 58 and 67 and which are suitably held thereto as by screws 126 and 127, respectively. The plate 124 carries the vanes 120. These plates between them form the walls of the pump chamber 79, the walls 121 and 122, the diffuser with its vanes 120 and intervening passages 123 and the outlet passage 81. All the surfaces of these elements may be formed with close accuracy by die casting, thus eliminating much expensive machining. The castings 58 and 67 are machined to receive the plates 124 and 125, respectively, but the machining required is simply plain facing and boring. The difficult surfaces to machine, including the curved surfaces and the tapered surfaces, are formed accurately and at low cost by die casting. As heretofore noted, the impeller also may be formed by die casting. Aside from the saving in cost, which is important, all the surfaces exposed to the liquid are formed with a smooth and polished finish, which results in a material reduction of the friction loss and a material increase in the efficiency of the pump. To secure polished surfaces formed with close accuracy, with the construction shown in Fig. 4, would require a large amount of time and expert hand labor.

The operation of the apparatus will now be described. The actual dispensing operation is accomplished in the usual way. The operator removes nozzle 36 from support 39, moves lever 25 in a clockwise direction (Fig. 1) to close the switch of motor 21 and thus start the pump in operation. He then inserts the nozzle in the tank to be filled and controls the flow with the nozzle valve, closing it when the register 32 of the meter shows that the desired quantity has 75

been delivered. He then replaces the nozzle on its support and moves lever 25 to stop the motor.

When the apparatus is first installed, it will be necessary to drive all air out of the system and this is accomplished by operation of the pumping unit with the valve of nozzle 36 held open. The displacement pump alone first functions in this operation, pumping out air and discharging it through pipe 40 to chamber 44 and then to the atmosphere until liquid has been drawn up in suction pipe 29 far enough to reach the impeller blades 88. Then the centrifugal pump becomes active and forces liquid up pipe 30, driving the air ahead of it until the meter 31, pipe 34, indicator 36 and the hose are entirely filled with liquid. Then the valve of nozzle 36 is closed and the system is ready for the normal operation.

Once the system is thus filled, this air-eliminating operation will not ordinarily need to be repeated. The foot valve or check valve associated with the suction pipe 29 will, if it closes tightly, maintain the pipe filled with liquid and the centrifugal pump primed. However, if and when this valve leaks, making priming of the centrifugal pump necessary, the work will be accomplished quickly and automatically by the displacement pump with a minimum of effort. This follows because the system on the discharge side of the centrifugal pump remains completely filled with liquid. The discharge chamber 16 of the centrifugal pump is below the level of the chamber 19 of that pump and consequently liquid does not drain back from the discharge side 35 of the pump to the suction pipe 29—the nozzle 36 being closed and there being no other way for air to enter the discharge line. Thus, when priming of the centrifugal pump is required, it is only necessary to exhaust the air from the chamber 19 of that pump and from the suction pipe 29. This is an important feature because it enables the priming to be quickly accomplished. It would be much slower if air had also to be exhausted from the discharge line because 40 the air expands during the exhausting process and it takes a long time to remove it all. If the system could completely drain, one would be obliged to repeat the operation used when the pump was first installed, and continual adjustments of the meter readings would be necessary, or corrections made to compensate for operation of the meter by air. So it is important, in order to avoid making such adjustments or corrections, to keep the discharge side of the system completely filled with air-free liquid.

In the normal operation, on the closing of the switch of motor 21, both pumps are simultaneously set in operation and, if the impeller blades 88 are submerged in liquid, the centrifugal pump 50 immediately begins its work. If not, the operation of the displacement pump will soon raise liquid to the elevation necessary for the purpose. The centrifugal pump not only supplies the necessary pressure to force the liquid through the discharge pipe, meter, hose and nozzle, but it also enables a very efficient separation of air and gases from the liquid to be effected under all conditions, irrespective of the amount of air and the viscosity of the liquid. The air-separating function takes place in the following manner. The impeller blades 88 whirl the liquid at a very rapid rate (say for example 3500 R. P. M.) and this whirling of the liquid extends far down into the suction pipe. This 55 pipe, at least at its inlet to the centrifugal pump,

is directed axially toward the same and in a manner such as to enable the whirling effect of that pump to be carried down into the suction pipe and form a vortex. The liquid, being heavier, is thrown outwardly while the air is forced radially inward toward the center of the vortex. The displacement pump scavenges this vortex, removing air and gases therefrom, whenever present, and with them some liquid and at other times liquid only, and discharging the same to the liquid recovery chamber 44. Here the air escapes to the atmosphere and the liquid is collected and returned from time to time, by way of pipe 51 to the suction pipe. The holes 89 enable the air and gases which cling as closely as possible to the hub 83 of the impeller, to rise directly into the overlying inlet port 99 of the displacement pump. This path of escape is thus the direct and natural one for air and gases which tend to rise. At the same time, the annular flange 89' which is preferably employed as described, prevents any possibility of a circulation of liquid around the impeller, as from the tips of blades 88 over the top of the plate 87 to holes 89 and thence downwardly to the inner ends of the blades 88. Such a circulation, involving as it does passage of fluid through holes 89 in a direction opposed to the planned direction of air flow through these holes, would interfere with the smooth operation of the displacement pump in its work of air removal. As it is, there are two separate and natural paths, one for liquid to the impeller blades of the centrifugal pump and one for air and gases to the rotors of the displacement pump. Since the latter has a capacity great enough to remove all air from suction pipe 29, it will naturally be more than sufficient to remove all the air and gases that travel up pipe 29 in or with the liquid, in the normal operation of the apparatus. Air and gases will thus be held within the central area of the impeller inside its blades and be kept from reaching said blades and passing to the discharge line and meter. Thus air-free liquid only can reach the meter.

Actually, considerable liquid will be discharged by the displacement pump and later returned to the suction pipe. However, little energy is required for this work because the pressure developed by the displacement pump is only that small amount necessary to raise the fluids the small distance to the chamber 44 which is always vented to the atmosphere. Heretofore, where separation has been accomplished in an accessory device, it has been necessary to raise all the liquid which is by-passed through the separator back to the suction line, to a substantial pressure—usually to the operating pressure of the pump (generally at least 15 lbs. per sq. in.). This requires considerable work and represents a substantial waste of energy. In some cases, as much as 15 per cent of the pump liquid, which has been raised to the heavy operating pressure, is by-passed back to the suction line. In the present case, a substantially less volume, say 10 per cent, is thus by-passed but none of this liquid is raised to the operating pressure of the pump nor indeed to any appreciable pressure at all. So the work of the displacement pump does not consume much energy.

The plan of air separation described does not require for its success any back pressure, as does the ordinary air separator used in gasoline dispensing systems as an accessory. In such systems, a check valve, usually opening only aft-

er at least five pounds pressure has been built up at the hose nozzle 36, is used. The use of such a valve means that additional pressure must be built up by the pump and more power consumed in doing it. Actually, no such valve is required for the air separating function described. It is simply necessary to whirl the liquid by the centrifugal pump and allow the vortex to form as described. However, to prevent draining of the hose when the apparatus is not in use, I use some sort of a valve at the nozzle 36 which valve can only be opened when pressure exists there but the pressure may be much less than that usually employed. And by reducing the back pressure due to this nozzle valve, the operating pressure can be reduced by the same amount and a substantial saving, around 20 per cent, made in the size of the motor and the power consumed. A smaller and thus cheaper motor may be used than can be in the usual meter-type gasoline dispensing apparatus, assuming equal volume of delivery in a given time in each case.

The centrifugal pump is utilized solely for pumping the liquid to be measured and then dispensed. No part of this liquid, which has to be raised to a substantial pressure, is returned to the suction line, as is usual. Thus, less power is required to operate it. Also, the motor need not have a high starting torque as is necessary where displacement pumps are used. The centrifugal pump builds up pressure gradually although in ample time for the purpose,—that is in the interval during which the operator, after having removed nozzle 36 from its support 38 and turned on the motor switch, carries the nozzle to the tank to be filled. The particular type of centrifugal pump illustrated has the advantage of maintaining a substantially uniform pressure, irrespective of the rate of liquid delivery, over a considerable range. Unlike other pumps of this general class, the pressure does not fall off sharply as the rate of delivery of liquid increases. For example, with the present pump, the pressure remains substantially constant for all rates of delivery up to 16 gallons per minute. Another advantage of the centrifugal pump is that no by-pass valve need be used with it to prevent building up excessive pressures in the discharge line when the pump is operated, as it often is, while the valve of the hose nozzle 36 is closed. At such times, the impeller of the centrifugal pump simply churns the liquid around in the pump chamber 79.

The particular type of centrifugal pump illustrated has a special advantage in a dispensing apparatus for gasoline and other relatively volatile liquids. It is not enough merely to pump the gasoline in the same way that water or other less volatile liquids are pumped by centrifugal pumps of ordinary form. For the special use described, the pump must be designed to avoid cavitation and the formation of eddies in the discharge chamber. Without a suitable diffuser cavitation can occur there and the liquid leaving the impeller will whirl around at high velocity in an area of reduced pressure. Partial vaporization of the gasoline may occur under certain conditions, depending on the vapor pressure of the liquid, its temperature and pressure; and the liquid delivered, as shown in the sight glass indicator 38, would have a foamy or milky appearance which is decidedly objectionable in the trade. The customer, seeing bubbles in the liquid, assumes them to be air bubbles and not,

as is the fact, air-free gasoline made foamy in appearance because of bubbles of partially-vaporized gasoline. The diffuser which may be of the form shown in Fig. 4 or the vane type shown in Figs. 13 and 14, prevents the dissipation in 5 eddies of the kinetic energy imparted to the gasoline by the impeller, and prevents cavitation. By the use of the diffuser, the velocity of the liquid discharged by the impeller is reduced gradually and without shock to the velocity of 10 the liquid in the discharge pipe. The necessary conversion of kinetic energy into pressure energy is effected smoothly and efficiently, without the formation of eddies,—resulting in a high pumping efficiency. The pressure is maintained more 15 nearly uniform, irrespective of rate of delivery, over a considerable range. While it is important and desirable to secure the efficiency of pumping, the really necessary and critical thing is to so discharge the liquid that it will not have the 20 objectionable milky or foamy appearance and this is secured by the use of a diffuser.

It is to be noted that the action of the centrifugal pump in whirling the liquid, removes any particles of foreign matter which may be carried 25 in suspension in the liquid, out of the inlet path to the displacement pump. The latter is thus protected against the entry of foreign matter which might, because of the closely fitting parts, interfere with its operation or cause undue wear 30 of the parts. The displacement pump is only required to pump clean liquid and air or gases. The allusion to foreign matter has reference to the very fine particles that are almost always present and are carried in suspension in the 35 liquid and are so fine that they are not removed by the screens or filters usually connected somewhere in the suction line to the pumping unit. There are no substantial quantities of solids entering this unit and the foreign matter, referred 40 to, passes through the centrifugal pump and out to, the discharge line as in other dispensing systems.

The motor-driven pumping unit is designed to enable substantial savings to be effected in cost 45 of manufacture over the apparatus heretofore used to do the equivalent work. The two pumps are directly connected to the shaft of the driving motor and are housed in a casing which includes as one element a special end plate for the motor,—thus affording a very compact arrangement. Separate mountings for the pumps and driving connections between each pump and the motor are dispensed with and the air separator accessory is no longer necessary since its work is 55 accomplished in the pumping unit. Additional savings in cost can be effected by the use of the die-cast linings for the centrifugal pump shown in Figs. 13 and 14.

The construction is also such that there are 60 few moving parts and few parts to wear and require servicing in the field. However, such servicing is readily accomplished when required. One simply removes the bolts 71, after the electrical connections to motor 21 have been broken, 65 after which the motor, displacement pump and the moving part of the centrifugal pump can be removed as one unit. No breaking of pipe connections is required and the work can be performed with only a very short interruption in the 70 use of the apparatus, especially if, as is often the case, a new unit is substituted for the old one and the latter sent to the factory for reconditioning. The displacement pump, however, is made as a separate unit and can be readily re- 75

5 moved (by simply removing the impeller 87 and cap screws 97) and a new unit substituted. In case the die-cast construction of Figs. 13 and 14 is used, it will also be necessary to remove screws 126 and plate 124. The centrifugal pump involving only the one moving part which is not subject to wear, should require no servicing. It will be seen that the design is such as to reduce to extreme simplicity the operation of servicing 10 and inspection.

15 The invention thus affords by the use of the composite pumping unit described, substantial savings in manufacturing cost and in the cost of servicing the apparatus in the field. It also results in much smoother and quiet operation. Its 20 use in a meter type gasoline dispensing apparatus enables air and gases to be separated from the liquid under all conditions regardless of the amount of air and the viscosity of the liquid, without the use of any additional apparatus for the purpose, and insures that air-free liquid only will be delivered to and measured by the 25 meter and that the air-free liquid discharged will have a clear appearance and be free from foam.

25 What I claim is:

30 1. In apparatus of the class described, an electric motor including its shaft and the end plates in which said shaft is rotatably mounted, a casing secured to one said end plate, such plate and casing forming between them a centrifugal pump chamber, said last named end plate having a recess therein adjacent said chamber, a displacement pump mounted in said recess and having 35 a rotatable member fixed to said shaft, and a centrifugal pump impeller located in said chamber and fixed to said shaft, said casing having therein an inlet for the centrifugal pump and outlets one for each pump, the displacement pump having its inlet in direct communication with said chamber.

40 2. In apparatus of the class described, an electric motor including its shaft and the end plates in which said shaft is rotatably mounted, a casing secured to one said end plate, such plate and casing forming between them a centrifugal pump chamber, said last named end plate having a recess therein adjacent said chamber, a displacement pump mounted in said recess and having a 45 rotatable member fixed to said shaft, a centrifugal pump impeller located in said chamber and fixed to said shaft, said last-named end plate having a bearing for said shaft axially spaced from the displacement pump and located on the opposite side thereof from said impeller, said last-named end plate having a chamber between the displacement pump and one side of said bearing, a seal ring mounted on said shaft in said last-named chamber and engaging the adjacent face of the displacement pump, said last-named end 50 plate having a vent passage leading from said last-named chamber to the atmosphere for the escape of any inflammable vapors which may pass said seal ring and having also on the opposite side of said bearing a flame arrester 55 encompassing said shaft and preventing the transmission of flame from within the motor along said shaft and through said bearing into said last-named chamber.

60 3. In apparatus of the class described, an electric motor including its shaft and its end plates in which said shaft is mounted, one said end plate having a central recess in its outer face encompassing said shaft, a displacement pump mounted in said recess and having a rotatable member fixed to said shaft, a casing secured to 65 the last-named end plate and cooperating with it to form a centrifugal pump chamber, a centrifugal pump impeller located in said chamber and fixed to said shaft, said casing having an inlet passage adapted for connection to an inlet pipe and extending axially to said chamber and a peripheral outlet passage leading from the chamber and adapted for connection to an outlet pipe, the inlet port of the displacement pump lying adjacent and communicating with said chamber, said last-named plate having an outlet 70 75

passage extending to said casing, said casing having a passage forming a continuation of said outlet passage and terminating with a port for connection to an outlet pipe, all constructed and arranged so that the motor with the displacement pump and said impeller may be removed as one unit leaving said casing connected to said several pipes.

4. In apparatus of the class described, an electric motor including its shaft and upper and lower end plates in which said shaft is mounted with its axis vertically disposed, the lower end plate having a central recess in its lower face encompassing said shaft, a displacement pump mounted in said recess for removal and replacement as one unit and having a rotatable member fixed to said shaft, a casing secured to the lower end plate and cooperating with it to form a centrifugal pump chamber, a centrifugal pump impeller located in said chamber and fixed to said shaft, said casing having an inlet passage adapted for connection to an inlet pipe and extending axially to said chamber and a peripheral outlet passage leading from the chamber and adapted for connection to an outlet pipe, the inlet port of the displacement pump overlying and communicating with said chamber, said lower end plate having an outlet passage extending to said casing, said casing having a passage forming a continuation of said outlet passage and terminating with a port for connection to an outlet pipe, and a fixed support for said casing, all constructed and arranged so that the motor with the displacement pump and said impeller may be removed as one unit leaving said casing on its fixed support and connected to said several pipes.

5. In apparatus of the class described, an electric motor including its shaft and the end plates in which said shaft is rotatably mounted, a casing secured to one said end plate, such plate and casing forming between them a centrifugal pump chamber, said last-named end plate having a recess therein adjacent said chamber, a displacement pump mounted in said recess and having a rotatable member fixed to said shaft, a centrifugal pump impeller located in said chamber and fixed to said shaft, said last-named end plate having a bearing for said shaft axially spaced from the displacement pump and located on the opposite side thereof from said impeller, said last-named end plate having a chamber between the displacement pump and one side of said bearing, a seal ring mounted on said shaft in said last-named chamber and engaging the adjacent face of the displacement pump, said last-named end plate having a vent passage leading from said last-named chamber to the atmosphere for the escape of any inflammable vapors which may pass said seal ring and having also on the opposite side of said bearing a flame arrester encompassing said shaft and preventing the transmission of flame from within the motor along said shaft and through said bearing into said last-named chamber.

6. Pumping apparatus, comprising, a centrifugal pump impeller having a member carrying on one face thereof a plurality of vanes and on the opposite face an axially directed annular collar, first and second casing sections one on each side of the impeller and secured together and forming between them a chamber to enclose the impeller, a drive shaft mounted in the first section and extending through said collar in spaced concentric relation and being secured to said impeller, said first section having in its inner face

- 5 a recess opening into said chamber, a displacement pump mounted in said recess and driven from said shaft, a die-cast plate inset into and covering the inner face of the first section and closing said recess except for a central opening through which said collar extends, said member having air passages through it close to the axis and inside said collar, the second section having inlet and outlet passages for said pump 10 chamber and cooperating with said die-cast plate to form the pump chamber and a diffuser connecting the pump chamber to the outlet passage.
- 15 7. Pumping apparatus, comprising, a centrifugal pump impeller having a member carrying on one face thereof a plurality of vanes and on the opposite face an axially directed annular collar, first and second casing sections one on each side of the impeller and secured together and forming between them a chamber to enclose 20 the impeller, a drive shaft mounted in the first

section and extending through said collar in spaced concentrical relation and being secured to said impeller, said first section having in its inner face a recess opening into said chamber, a displacement pump mounted in said recess and 5 driven from said shaft, a die-cast plate inset into and covering the inner face of the first section and closing said recess except for a central opening through which said collar extends, said member having air passages through it close to 10 the axis and inside said collar, the second section having inlet and outlet passages for said pump chamber and cooperating with said die-cast plate to form the pump chamber and a diffuser passage connecting the pump chamber to the 15 outlet passage, said plate having diffuser vanes extending in the diffuser passage and abutting the second named member.

WARREN H. DE LANCEY. 20
